UNITED STATES PATENT OFFICE.

NORVIN J. STEINAU, OF LOUISVILLE, KENTUCKY.

ADVERTISING DISPLAY SIGN.

Application filed January 9, 1922. Serial No. 527,826.

To all whom it may concern:

Be it known that I, NORVIN J. STEINAU, a citizen of the United States, residing at Louisville, in the county of Jefferson and State of Kentucky, have invented certain new and useful Improvements in Advertising Display Signs, of which the following is a specification.

This invention has to do with an improved advertising display sign. It has reference particularly to an improved construction of display sign for use in windows and similar locations.

The main object of the invention is to provide a display sign which when in place against the glass of the window will have an appearance very similar to that created by the attachment of letters and other symbols to the face of the glass as is frequently done, but which sign may be manufactured and put into place against the window at a very small cost compared to the usual and ordinary cost of letters as attached to a window in the manner which is customary and well known.

Another object of the invention is to provide a display sign which when in place against the glass will present a very attractive and artistic appearance, and one superior in many respects to the appearance of letters and symbols as previously attached to the window.

Another object of the invention is to provide a display sign of such construction that the outlines of the letters and other symbols themselves will be emphasized against the background as viewed by a person looking into the window from the outside. In this connection, another object is to so design and construct the display sign as to take advantage of the usually darkened interior of the store or room so as to emphasize the outlines of the symbols and letters of the display sign itself.

Another object of the invention is to provide a display sign which may be very easily and quickly attached to the window in a relatively permanent and secure manner.

Other objects and features of the invention will appear from a detailed description of the same, which consists in the features of construction and combinations of parts hereinafter described and claimed.

Referring to the drawing:

Figure 1 shows a front face view of a

simple display sign embodying the features of the present invention; and

Fig. 2 shows a longitudinal section taken on the line 2—2 of Fig. 1, looking in the direction of the arrows, the sign being shown as applied to a window or the like.

The advertising display sign of the present invention comprises essentially a sheet of card board or paste board cut to the desired exterior configuration, and having its face portion cut and ornamented in the proper manner to provide the desired display figures and symbols. The particular sign illustrated in the drawing is for "Oak Hill Coffee," and the exterior configuration of the sign is so cut that the outlines of the upper portions of the letters are established by the configuration of the sign itself, and in like manner the outlines of the lower portions of the letters are similarly established by the configuration of the sign itself. In addition to the foregoing, the outlines of any other figure, such as the figure of the can of coffee, are established by the contour of the sign itself.

The background of the sign is colored generally a dark color or a dead black as shown in the drawing. The outlines of the lower portions of the upper letters and of the upper portions of the lower letters are completed by the proper shaping of the background as is clearly evident from Fig. 1. Furthermore, the peripheral portions of the various letters or similar symbols are emphasized by relatively heavy outlines such as shown at 3 and 4 in Fig. 1 for the letters O and A respectively. Consequently, the central portions 5 of these letters stand out with greater clearness and emphasis. This effect is emphasized by making the peripheral portions of the letters either dead black to conform with the background, or of the same dark color as the background if it be other than dead black.

The background of the sign and the peripheral portions of the various letters lie in a flat plane, so that when the sign is applied directly against the window pane, these portions will lie flush against the glass. On the contrary, the body portions of the letters are upset a very substantial distance as shown in Fig. 2, so that when the sign is set into place against the window pane these body portions of the letters stand a considerable distance away from the glass.

This form and construction of the sign is readily produced by the proper upsetting or embossing operation either simultaneously with the cutting of the outline contour 5 or subsequently.

Furthermore, the central portions of the letters or symbols are colored a contrasting color as compared to the background of the sign, so that the forms of these letters and 10 symbols will stand out against the background of the sign with great emphasis and force. For example, in those cases in which the background of the sign is dead black, the body portions of the letters and symbols 15 may advantageously be made of gold or silver color and this is the combination which it is contemplated will be most frequently used.

When the background of the sign is made 20 dead black and the body portions of the letters and symbols are of gold or silver, a very striking appearance is produced when the sign is set against the inside face of a window so as to be visible to persons on 25 the outside. This is because the black background of the sign itself tends to merge with the relatively dark interior of the store or other room and therefore the background of the sign itself is not in evidence, but the 30 observer has emphasized to his notice the gold or silver letters and other symbols in a forcible manner. Owing to the upsetting of the letters in the manner clearly illustrated in Fig. 2, and particularly in those 35 cases in which this upsetting is of a beveled or V form, the shading of the two sides of the upset portion is emphasized, since the light striking the same is reflected in different directions. The result is that the sign 40 presents an appearance strikingly similar to that created by the attachment of porcelain or other similar letters to the surface of the window in the manner well understood and practiced heretofore.

45 The sign itself may be readily attached to the window pane as a unit, and this attachment may be effected in any convenient

manner. I prefer, however, to provide at each end of the sign, or at convenient points around its periphery, gummed tabs 6 whose 50 front faces are gummed so that they may be readily attached to the surface of the window after being moistened.

While I have herein shown and described only a particular form of sign embodying 55 the features of the present invention, still I do not limit myself thereto except as I may do so in the claim.

I claim:

As a new article of manufacture, an advertising display sign for use in conjunction with the surface of a window or the like, said sign being provided with letters or other symbols, and said sign comprising a blank of material having its peripheral 60 portion cut to the desired contour to establish the peripheries of the lower portions of the symbols and to establish the peripheries of the upper portions of the symbols, the body portion of each symbol being upset 65 or embossed, the peripheral portion of each symbol and a portion of the central portion of the body of the sign being flat and adapted to lie in flush manner against the surface of the window, said flattened portions being 70 of a dark color, and the upset portions of the symbols being of a brightly contrasting color, and means for securing the sign to the surface of the window with its flat face lying 75 flush against the window and with its upset portions projecting away from the surface of the window, comprising a pair of gummed tabs connected to the sign and adapted for attachment to the surface of a window pane, whereby, when the sign is in 80 place against the surface of the window, the relatively dark peripheral portions of the symbols and of the body of the sign merge with a relatively darkened interior, and whereby the body portions of the symbols 85 are emphasized to the observer, substantially as described.

NORVIN J. STEINAU.
